CLAIM

The ornamental design for a combination device for tobacco grinding, sorting and loading, as shown and described.

DESCRIPTION

FIG. 1 is perspective view of the combination device for tobacco grinding, sorting and loading showing the new design thereof.

FIG. 2 is an enlarged, partial perspective view of the combination device for tobacco grinding, sorting, and loading shown in an alternate configuration and with a symbolic break.

FIG. 3 is a first-side elevational view of the combination device for tobacco grinding, sorting, and loading shown in FIG. 1.

FIG. 4 is a second-side elevational view of the combination device for tobacco grinding, sorting, and loading shown in FIG. 1.

FIG. 5 is a third-side elevational view of the combination device for tobacco grinding, sorting, and loading shown in FIG. 1.

FIG. 6 is a fourth-side elevational view of the combination device for tobacco grinding, sorting, and loading shown in FIG. 1.

FIG. 7 is a top plan view of the combination device for tobacco grinding, sorting, and loading shown in FIG. 1; and, FIG. 8 is a bottom plan view of the combination device for tobacco grinding, sorting, and loading shown in FIG. 1.

In the drawings, the broken lines depict portions of the combination device for tobacco grinding, sorting, and loading that form no part of the claimed design. The additional broken lines shown in FIGS. 1 and 7 depict environment only and form no part thereof. The central, cylindrical body is shaded for transparency. Additional surface shading is included to aid in understanding the design. Portion(s) of the combination device for tobacco grinding, sorting, and loading that would normally be visible, but are not shown in the drawing or described in the specification, are not part of the claimed design.

1 Claim, 7 Drawing Sheets
